UNITED STATES PATENT OFFICE.

WILLIAM E. WHITE, OF CHICAGO, ILLINOIS.

CHAIR FOR CONCRETE BARS.

Application filed July 23, 1921, Serial No. 486,973. Renewed March 28, 1924.

To all whom it may concern:

Be it known that I, WILLIAM E. WHITE, a citizen of the United States, and resident of Chicago, in the county of Cook and State of Illinois, have invented certain new and useful Improvements in a Chair for Concrete Bars, of which the following is a specification.

My invention relates to concrete reinforcement and particularly to a novel chair for use in connection therewith.

One of the objects of my invention is to provide a chair adapted especially for concrete road work. It is customary to lay concrete composing the roads directly on the soil after it has been suitably leveled or graded. It has been customary to reinforce such roadways and difficulty has been experienced in providing supports or chairs for the bars previous to the placing of the concrete. In the device of my invention I provide a chair having supporting legs, portions of which are adapted to enter the soil and provide a stable structure. In addition I provide means for bracing the legs, such means also constituting the limit stop for determining the extent to which the legs enter the soil. The structure is, of course, adapted for use as a highchair in ordinary reinforcing work where forms are employed, and therefore is not limited to a use such as that illustrated in the drawings.

The invention will be more readily understood by reference to the drawing, wherein, Fig. 1 is a side elevation of a chair constructed in accordance with my invention, a reinforcing bar being shown in section;

Fig. 2 is a view taken at right angles to that of Fig. 1; and

Fig. 3 is a sectional view of the chair on the line 3—3 of Fig. 1.

In the drawings it will be seen that the chair consists of a U-shaped member having a horizontal portion 10, and legs the portions 11 of which are inclined and the portions 12 of which are vertical. It also includes members having portions 13 which are inclined oppositely to that of the portions 11, and portions 14. There are two of such members and they are welded near their upper ends to the horizontal portions 10 of the U-shaped member, the welding being done at such points that portions 15 project above the horizontal member and provide with the horizontal member a seat within which a reinforcing bar 16 is accom-

modated. The legs are braced and bound together by means of a generally rectangular ring or hoop 17 formed of wire, the ends of which are welded together and 60 welded at the corners to the legs. The position of the rectangular bracing member, relative to the lower ends of the legs, determines the extent to which the chair is allowed to enter the soil, this being shown 65 in Figs. 1 and 2. One of the substantial advantages in the use of a chair such as shown is in the ease of application, the simplicity of the device and the certainty of stability under all normal conditions. 70 Being constructed of wire throughout there is no waste metal and it may be very cheaply constructed.

The form of the braces may vary to a considerable extent and still perform the 75 same functions, and other modifications in the shape of the parts may be made without departure from the spirit of my invention.

I claim:

1. In a reinforcing chair, the combination of a U-shaped member the longitudinal parts of which constitute legs and the horizontal part of which constitutes a support for a bar, a pair of legs welded to said U-shaped member and having portions projecting above the horizontal part thereof, and bracing means secured to said legs at a point between their ends.

2. In a chair, the combination of a wire bent to provide a horizontal portion and legs, a second pair of legs welded at their upper ends to said horizontal portion and having portions projecting above said horizontal portion to constitute a seat for a bar, and means joining and bracing all of 95 said legs at a point between their ends.

3. A chair for reinforcing elements of concrete roads, comprising in combination a U-shaped member having a horizontal portion and legs, said legs being arranged in 100 parallelism with their upper portions inclined to the vertical and their lower extremities in a substantially vertical position, a second pair of legs similarly shaped and welded to said first pair, means projecting 105 above the horizontal portion of said first pair of legs for defining a seat for a reinforcing bar, and means for bracing said legs.

4. A chair for reinforcing elements of 110 concrete roads, comprising in combination a U-shaped member having a horizontal por-

- tion and legs, said legs being arranged in parallelism with their upper portions inclined to the vertical and their lower extremities in a substantially vertical position, 5 a second pair of legs similarly shaped and welded to said first pair, means projecting above the horizontal portion of said first pair of legs for defining a seat for a reinforcing bar, and means for bracing said 10 legs, said last named means being located at substantially the junction of the inclined and vertical portions of said legs.
5. In a chair for use in concrete road work, the combination of a plurality of 15 legs having their upper ends inclined to a central meeting point and the lower ends of the legs in a vertical position, portions of certain of said legs projecting above portions of the other legs whereby to constitute a seat for a reinforcing rod, and bracing and joining means located at the junction between the inclined and vertical portion of said legs.
6. In a chair, the combination of a U-
- shaped member composed of wire and having a horizontal portion and two legs, a second pair of legs welded at their upper ends to said horizontal portion and having projections above said horizontal portion, and a wire ring of substantially the contour 30 of said legs at an intermediate point in the length thereof and welded to said legs to serve as bracing means therefor.
7. In a device of the class described, the combination of a wire structure providing 35 a seat for a reinforcing member at the upper end of the device, and braces between the ends thereof, said legs extending vertically relative to the support for the device, said 40 braces having the double function of bracing the legs and acting as limit stops for the downward motion of the device when placed in soil.

Signed at Chicago, Illinois, this 19th day 45
of July, 1921.

WILLIAM E. WHITE.
